US0D1021515S

(12) **United States Design Patent** (10) Patent No.: **US D1,021,515 S**
(45) Date of Patent: ** Apr. 9, 2024

(54) **COOKING CUP**

(71) Applicant: **LOCK & LOCK Co., Ltd**, Asan-si (KR)

(72) Inventor: **Dong Seop Shim**, Yongin-si (KR)

(73) Assignee: **LOCK & LOCK Co., Ltd**, Asan-si (KR)

(**) Term: **15 Years**

(21) Appl. No.: **29/809,649**

(22) Filed: **Sep. 29, 2021**

(30) **Foreign Application Priority Data**

Apr. 8, 2021 (KR) 30-2021-0017006

(51) LOC (14) Cl. **07-02**

(52) U.S. Cl.

USPC **D7/361**; D10/46.2
